UNITED STATES PATENT OFFICE.

FRANK HENGESBACH, OF WILLOUGHBY, OHIO, ASSIGNOR TO HIMSELF,
JAMES W. PENFIELD, AND RAYMOND C. PENFIELD, ALL OF SAME PLACE.

ROOFING-TILE AS AN ARTICLE OF MANUFACTURE.

SPECIFICATION forming part of Letters Patent No. 340,668, dated April 27, 1886.

Application filed November 4, 1885. Serial No. 181,816. (Specimens.)

To all whom it may concern:

Be it known that I, FRANK HENGESBACH, of Willoughby, in the county of Lake and State of Ohio, have invented certain new and 5 useful Improvements in Roofing-Tile as an Article of Manufacture; and I do hereby declare the following to be a full, clear, and exact description of the invention, such as will enable others skilled in the art to which it pertains to make and use the same.

My invention relates to a roofing-tile as an article of manufacture, the same being colored to imitate roofing-slate, with the color extending through the body of the tile, to the 15 end that a cheap and durable roofing-tile is made, that if broken the fractures will show substantially the same color as the outside of the tile.

This tile is made from the same material 20 from which ordinary bricks and tiles are made and is burned in the kiln in the same manner. At the end of the burning process, while both the tiles and kiln are in a highly-heated condition, a quantity of wet fuel—either coal 25 saturated with water or green wood soaked in water—is placed in the furnace of the kiln and the latter hermetically closed. The heat of the furnace converts the water of the fuel into steam and expels the gases from the fuel 30 in the form of smoke. The combined smoke and steam permeates the body of the tiles and colors them throughout. The color thus produced resembles the color of ordinary roofing-slate, and the shade of color will be lighter or 35 darker according to the amount of wet fuel that is used.

A preferable way of closing the kiln to exclude the air is by means of double doors and spaces in the walls of the kiln, said spaces in 40 the walls and between the doors being filled

with fine sand; also, the outer walls of the kiln may be carried up a few inches above the roof of the kiln and a quantity of water kept in the reservoir thus formed of sufficient depth to cover the top or roof of the kiln.

The coloring process usually requires about three days, after which the kiln and product are allowed to cool down and the tiles are removed.

In the accompanying drawings, Figure 1 is 5 a view in perspective of a preferable form of roofing-tile. Fig. 2 is an edge view in longitudinal section through the center of the tile. Fig. 3 is an edge view in transverse section through the center of the tile. Fig. 4 is a 5 view in perspective showing several tiles in position.

The tile A is of a well-known form, and is in common use, and it is therefore not considered necessary to describe it.

The tile A or any other desired form may be used in carrying out my invention—to wit: a tile colored to imitate the color of ordinary roofing-slate, with the color extending through and through the body of the tile.

What I claim is—

As an article of manufacture, a roofing-tile colored to imitate the color of ordinary roofing-slate, the color of the tile extending through the body of the tile, so that a fractured part of the tile will show substantially the same color as the outside of the tile.

In testimony whereof I sign this specification, in the presence of two witnesses, this 11th day of June, 1885.

FRANK HENGESBACH.
